UNITED STATES PATENT OFFICE.

JUDSON L. THOMSON, OF SYRACUSE, NEW YORK.

DESIGN FOR A TONGUE FOR SHOE-CLASPS.

SPECIFICATION forming part of Design No. 15,626, dated December 16, 1884.

Application filed October 31, 1884. Term of patent 7 years.

To all whom it may concern:

Be it known that I, JUDSON L. THOMSON, of Syracuse, in the county of Onondaga, in the State of New York, have invented and produced a new and original Design for Tongues for Shoe-Clasps, of which the following, taken in connection with the accompanying drawing, is a full, clear, and exact description.

My design consists of an elongated plate having one end broad and curved uniformly in outline, its central portion contracted and reverse curved in outline, and the opposite end flaring, and a central longitudinal slot widened from the center toward opposite ends, as shown in the annexed drawing, which represents my design.

A denotes the elongated plate; a, the broad end thereof, curved uniformly in outline. b is the contracted central portion of the plate, reverse curved in outline, and c is the flaring end of the plate. s represents the central longitudinal slot, which is widened from the center toward opposite ends.

A tongue of the form above described presents a light and neat appearance.

25

What I claim is—

The design for the tongue of a shoe-clasp, consisting of the elongated plate A, having the broad end a, curved uniformly in outline, the contracted central portion, b, reverse curved 30 in outline, and the flaring end c and the central longitudinal slot, s, widened from the center toward opposite ends, substantially as described and shown.

In testimony whereof I have hereunto signed my name and affixed my seal, in the presence of two attesting witnesses, at Syracuse, in the county of Onondaga, in the State of New York, this 29th day of October, 1884.

JUDSON L. THOMSON. [I. S.]
